HAROLD C. HARVEY, OF MILWAUKEE, WISCONSIN, ASSIGNOR TO MILWAUKEE LACE PAPER COMPANY, OF MILWAUKEE, WISCONSIN.

NESTING-MACHINE.

1,323,632.

Specification of Letters Patent. Patented Dec. 2, 1919.

Application filed July 24, 1918. Serial No. 246,494.

To all whom it may concern:

Be it known that I, HAROLD C. HARVEY, a citizen of the United States, and resident of Milwaukee, in the county of Milwaukee, 5 and State of Wisconsin, have invented certain new and useful Improvements in Nesting-Machines; and I do hereby declare that the following is a full, clear, and exact description thereof.

10 The present invention relates to new and useful improvements in machines for nesting cup-shaped articles whereby they may assume a most compact relation for storage or shipping, a particular application of the 15 machine being the nesting of bon bon or the like cups, stamped from a single sheet of paper.

It is primarily the object of the present invention to provide a simple machine 20 whereby this nesting operation may be carried out in a most ready manner and wherein the placing of the cups by an operator for the nesting operation is facilitated so that an operator not necessarily skilled in 25 the use of the machine can readily feed cups thereto for a desired rapid operation of the machine.

Paper cups of the bon bon type, stamped from a single sheet of paper, usually assume 30 a nearly cylindrical shape as they are discharged from the forming dies, and it is a further object of the invention to provide means for spreading the cups to insure their movement into nesting relation prior to 35 nesting engagement of the cup by the machine.

A further object resides in the provision of a machine of this character which is adjustable for reception of cups of various 40 diameters.

With these and other objects in view, which will be apparent as the description proceeds, my invention resides in the novel features of construction, combination and 45 arrangement of parts as hereinafter described and defined by the appended claims, it being understood that changes in the precise embodiment might be made by those skilled in the art without departing from 50 the spirit of the invention.

This invention in one practical form in which it may be embodied is illustrated in the accompanying drawing in which:—

Figure 1 is a side elevational view of

a nesting machine embodying the present 55 invention.

Fig. 2 is a horizontal sectional view through the machine on the line 2—2 of Fig. 1.

Fig. 3 is a vertical sectional view on the 60 plane indicated by the line 3—3 of Fig. 1 through the nesting throat and adjacent portions of the machine.

Fig. 4 is a detail sectional view on the line 4—4 of Fig. 1 showing the spreading mecha- 65 nism in plan.

Fig. 5 is a perspective view of one of the 70 cups for the nesting operation on which the present embodiment of the invention is particularly adapted.

Fig. 6 is a detail sectional view on the plane of Fig. 3, showing the means for adjusting the machine for different sizes of cups.

Referring now more particularly to the 75 accompanying drawings, the machine includes a main frame comprising the base 10 having a standard 11 rising from its rear and having a standard 12 rising from its front portion and supporting a horizontal 80 bar 13, the ends of which support the ends of an arch 14 from which rises a standard section 15 connected at its upper end with the upper portion of the standard 11 by a top transverse sill 16. An intermediate 85 transverse sill 17 connects the top of the arch with the intermediate portion of the standard and the lower transverse sill 18 connects the lower portion of the standard 11 with the horizontal bar 13, this sill being 90 cut away for the reception of a throat block 19 provided with a pair of throat passages 20 extending vertically therethrough and in radial alignment with a shaft 21 journaled in a bearing arm 22 projecting forwardly 95 from the standard 12. The upper end of the shaft carries a head plate 23 on which is secured to a turn table 24 provided with a series of radial pairs of cup seating openings 25 adapted to successively align with the throats 100 20. This turn table is movable over a stationary table 26 secured on the sill 18 and horizontal bar 13 and provided with a central opening receiving the head plate 23 and further provided with a pair of openings 105 27 receiving upstanding annular flanges on the throat block 19 surrounding the throats 20 whereby an uninterrupted throat passage

is afforded from the seating openings 25 of the turn table. Thus, upon rotation of the turn table, pairs of cups may be successively carried into alignment with the throats for movement therethrough, and while I have shown a pair of nesting throats, it is obvious that but a single throat or any number of throats may be employed, in conjunction with a corresponding arrangement of seating openings.

For receiving and conveying nested cups from the throats, a pair of chutes are provided in the form of a double chute-way, extending downwardly from the throats and

then laterally of the machine. This double chute way comprises a central guide strip 28, common to the sides of both chute passages, a pair of bottom strips 29 and a pair of outer guide strips 30, these strips being connected

together at their upper ends and at spaced portions along their stretches by transverse bars 31, each secured at its central portion to the center strip 28 and then bent rearwardly and bent outwardly therefrom for secu-

rement to the outer sides of the strips 29 and then bent inwardly for securement to the outer sides of the strips 30, each of these transverse strips thus forming a pair of connected U-shaped portions. The connecting

member at the upper ends of the chute strips is provided with an outwardly extending lug 32 and this lug is engageable by a screw 33 carried by an angular bracket 34 depend-

ing from the frame sill 18 and adapted to clamp said connecting member against the throat block, which in turn is clamped against the sill by means of seating shoulders on its base portion whereby all of these parts are secured in assembled relation, but

may be readily detached for the substitution of throat blocks and channel ways of different sizes to adapt the machine for operation on different sizes of cups.

For moving the cups through the nesting throats a shaft 35 is journaled in the upper end of the standard 11 and in a bearing 36 on the sill 13, and this shaft carries on its inner end a crank wheel 37 from which extends a stub shaft 38 connected by pitmen 39 with a pair of plunger shafts 40 slideable in the sills 16 and 17 and carrying plunger heads 41 on their lower ends adapted to move through the seating openings of the turn table and through the plunger throats

for nesting cups carried over the throats by the turn table. The shaft 35 is driven through the medium of a set of reducing gears 42 connecting it with a shaft 43 carrying a belt wheel 44, and the outer end of the shaft 35 carries a balance wheel 45.

For rotating the turn table in successive steps, synchronized with the operation of the plungers, a vertical shaft 46 is journaled in the frame sills and base and is driven from the shaft 35 through the medium of

intermeshing bevel gears 47. This shaft carries a gear wheel 48 meshing with a gear wheel 49 mounted on a shaft 50 carried by a bearing arm 51 projecting laterally from the sill 18. Mounted on the shaft 50 is a crank wheel 52 to which is pivoted one end of the pitman 53 having its other end pivoted to a rock arm 54 which is mounted on the turn table shaft 21. A pawl 55 has one end pivoted to the rock arm and is engageable with a series of ratchet teeth 56 cut into the periphery of the turn table, this pawl being normally urged toward the turn table by a retractile spring 57 secured thereto and to the rock arm. The outer end of the rock arm is supported on a guide arm 58 projecting from the frame bar 13. Thus upon continuous rotation of the shaft 46, the pitman will be oscillated to procure successive rotative steps of the turn table through the medium of the pawl 55. The turn table is held against excessive rotative movement under influence of the pawl by a leaf spring 59 secured to one end of the arch 14 and bearing against the periphery of said turn table.

To effect a spreading of the cups prior to their movement over the throats 20, whereby their proper nesting engagement is assured upon depression through the throats, a bar 60 is secured on the lower portions of the plunger shafts 40 and adjustably carries a pair of arms 61, having depending spreader heads 62 of inverted conical shape at their free ends, the connection of these arms 60 to the bar being effected by clamping bolts 63 passed through the ends of the bar and through longitudinal slots 64 in the ends of the arms. These spreader heads are engageable in cups seated in the turn table, openings 25 immediately succeeding the cups in nesting alignment with the throats 20, and a spreading operation is obviously carried out simultaneously with the nesting operation. The slotted connections of the arm 61 permit their adjustment for seats of various sizes in the turn table.

As shown in Fig. 6, the sizes of the seats of the turn table may be varied by inserting bushings 65 having various internal diameters, in the seating openings 25 of the turn table, and this adaption for different sizes of cups is carried out in conjunction with the securement of a throat block 19 and chute ways adapted for a corresponding size of cup. Thus the machine may be readily adapted within reasonable limits for various sizes of cups.

It is a common practice to form a number of cups of the present character in a single dieing operation, the cups remaining nested, with their walls fluted as shown in Fig. 5, and the machine is adapted for operating upon such simultaneously formed batches of cups, treating them as a single

cup member, the spreader heads 62 serving to overcome the difficulty of nesting which might be occasioned by the separating tendency of the walls of such simultaneously formed batches of cups.

5 An exceedingly simple machine has thus been provided which may be operated by a person not necessarily skilled, at a very rapid speed, it being noted that practically 10 the entire area of the turn table is available for the placing of cups in the seats thereof, and that no interruption to the operation of the machine occurs should any number of empty seat openings pass under the plunger 15 heads.

While I have described the movable cup carrying table of the machine as a turn table, it is obvious that any table member movable in regular steps under the plunger 20 heads may be employed, and that various changes of structure, to meet differing conditions of use, may be employed in any manner, without departing from the spirit 25 of my invention.

25 What is claimed is:

1. A nesting machine including a chute, a table provided with a series of cup seating openings and movable in successive steps over the chute, a plunger reciprocable 30 to force cups from said seat openings into the chute, and means for spreading cups in said seat openings prior to their movement over the chute.

2. A nesting machine including a chute, a table provided with a series of cup seating openings and movable in successive steps over the chute, a plunger reciprocable to force cups from said seat openings into the chute, and means carried by the plunger 40 for spreading cups in said seat openings prior to their movement over the chute.

3. A nesting machine including a chute, a table provided with a series of cup seating openings and movable in successive 45 steps over the chute, a plunger reciprocable to force cups from said seat openings into the chute, and means carried by the plunger for spreading cups in said seat openings prior to their movement over the chute, including a lateral arm on the plunger, and a spreader head of inverted conical shape carried by the arm and engageable with cups in the seat openings prior to their movement over the chute.

55 4. A nesting machine including a frame, a block detachably carried by the frame and provided with a nesting throat extending therethrough, a stationary table having its upper surface flush with the mouth 60 of the throat, a table movable over the sta-

tionary table and throat and provided with openings adapted to register with the throat, seat adjusting bushings disposed in said openings, a chute disposed under the throat block, and a plunger movable 65 through the throat block and openings registered therewith for forcing cups into the chute.

5. A nesting machine including a frame, a block detachably mounted upon the frame 70 and provided with a nesting throat extending therethrough, a chute detachably carried by the frame and extending from the throat, a table movable over the throat and provided with openings adapted to register 75 with the throat, means for procuring successive step movements of the table, adjusting bushings in the openings of the table, and a plunger carried by the frame and adapted to move through the throat and 80 openings registered therewith for forcing cups into the chute.

6. A nesting machine including a set of chutes, a table movable over the chutes and provided with sets of cup seating openings 85 adapted to register with the chutes, means for moving the table in successive steps for registry of its sets of openings with the set of chutes, a plurality of plungers simultaneously movable through the openings for 90 forcing cups seated therein into the chutes, adjusting bushings in the openings of the table, arms adjustably carried by the plungers and extending laterally therefrom, and spreader members depending from the 95 arms.

7. A nesting machine including a frame, a chute carried by the frame, a turn table carried by the frame and having one side disposed over the chute and provided with 100 an annular series of openings adapted to register with the chute, a plunger reciprocable above the turn table and movable through the openings thereon upon registry with the chute for forcing the cups into the 105 chute, a drive shaft mounted on the frame, a crank connection between said drive shaft and the plunger, a rock arm pivoted under the turn table, a pawl pivoted on the rock arm and resiliently urged toward the turn 110 table, a series of ratchet teeth on the turn table co-operating with the pawl, a second shaft driven from the drive shaft, and a pitman connection between said second shaft and the turn table.

In testimony that I claim the foregoing I have hereunto set my hand at Beloit, in the county of Rock and State of Wisconsin.

HAROLD C. HARVEY.
